UNITED STATES PATENT OFFICE.

JOHN BRADEN, OF FRANKLIN, PENNSYLVANIA.

SAND-PUMP.

SPECIFICATION forming part of Letters Patent No. 449,663, dated April 7, 1891.

Application filed November 21, 1890. Serial No. 372,133. (No model.)

To all whom it may concern:

Be it known that I, JOHN BRADEN, a citizen of the United States, residing at Franklin P. O., in the county of Venango and State 5 of Pennsylvania, have invented certain new and useful Improvements in Sand-Pumps; and I do hereby declare the following to be a full, clear, and exact description of the invention, such as will enable others skilled in the 10 art to which it appertains to make and use the same.

The invention relates to certain new and useful improvements in what are known in the art of well-boring as "sand-pumps" or 15 "bailers." It has special reference to the construction and arrangement of the valve at the lower end of these pumps, the object being to provide a self-closing inwardly-opening valve, which when opened to discharge 20 the contents will permit the free escape of sand, gravel, stones, pieces of rock, and other large obstructions along with the sand.

As heretofore constructed the lower end of the pump has generally been provided with 25 an annular valve-seat around its inner wall, and in connection therewith a ball or hemispherical gravitating-valve has been arranged to rise and fall in the pump-barrel. This form of valve has been found in practice to 30 have the objectionable feature of not permitting the free discharge of settled sand or gravel nor of stones and other obstructions, which are constantly falling into the open top of the barrel. This is owing to the fact 35 that in order to work successfully the diameter of the valve must be so great as to leave only a narrow annular space between its outer edge and the inner wall of the tube, so that no matter how wide the valve may be opened, 40 frequently the borings, sand, and gravel, as also rocks, stones, and other obstructions, cannot pass the ball so as to be discharged out through the valve-opening beneath. I overcome this objection by the construction and 45 arrangement hereinafter described and claimed, and illustrated in the accompanying drawings, wherein—

Figure 1 is a side elevation of my improved pump or bailer. Fig. 2 is a central longitudinal section thereof. Fig. 3 is a perspective view of the valve detached, and Fig. 4 is a cross-section taken just above the valve.

In the drawings, A denotes the pump barrel or tube, made, as usual, several feet in length, and of a diameter suitable to the bore 55 of the well wherein it is to be used. This tube is generally left open at the top; but I prefer to construct it with a closed end, as shown, though it is by no means essential, my improved valve being adapted to work 60 with either form. As a convenient means for closing this upper end, the stopper B screwed into the open mouth is a cheap and convenient expedient, though a cap fitting over the end would probably answer as well. When 65 the upper end of the barrel is closed, it is necessary to form openings, as C, in the sides near the end to permit the escape of air as the sand and water rushes in at the lower end.

Upon or to the lower end of the barrel is 70 firmly secured the hollow cap D, forming the seat for the valve E and guiding and controlling the valve in its movements up and down. This cap may be screwed onto the end of the barrel, as shown, so as to be readily 75 removed for repairs or replaced by a new one, or it may be riveted or otherwise permanently fastened thereto. One side and a portion of the end of this cap is cut away, as represented at d in the drawings, and the opening thus 80 formed constitutes a segmental valve-orifice for the discharge of the contents. The valve E is peculiarly constructed to co-operate with this valve seat and opening. As shown in the several views, it is formed with the main 85 body portion e, having a curved outer surface closely fitting the bore of the barrel when the valve is shoved up into the tube and completely closing the valve-opening when allowed to fall. The inner face of the valve is 90 flat, as shown at e'. The body portion of this valve is in fact a segment or a longitudinal section of a solid cylinder whose diameter is only sufficiently less than the internal diameter of the pump-barrel to allow 95 it to work freely therein. At its upper end the valve is provided with a thin cross-head d', standing transversely across the valve and playing up and down in the tube above the valve-opening, so as to guide the valve proper 100 in its movements, the cross-head being of a length equal to the diameter of the tube. The uncut-away portion of the bottom of the cap D is slotted, as shown at c, and in this

slot plays the stem *s* of the valve. The stem is preferably provided with a foot *f*, which also abuts against the bottom of the cap and acts as a stop to prevent the valve passing 5 too far up into the barrel when the end of the pump is struck on the ground to open the valve. As shown in Fig. 2, the valve is made large enough to overlap the edges of the cut in the cap *D*, so as to form a tight 10 joint.

P denotes a piston-head of ordinary construction, and *P'* the rod by which it is operated, the latter being guided by yoke-piece *F*, formed on the stopper *B* or cap.

15 The operation of the pump is very simple and will be readily understood by those skilled in the art. Particular attention being directed to the valve and its action, it will be noted that when the bailer is withdrawn 20 from the well and its end dropped or tapped lightly on the ground to open the valve, as is commonly done where this class of valves is used, the valve passes up into the barrel in practically the same way as 25 others of its class. Owing to the peculiar shape, construction, and arrangement of the valve, however, a much larger opening is provided for the discharge of the contents of the pump than in any other pump now in use. 30 Upon reference to Fig. 4 of the drawings, it will be seen that the body of the valve occupies less than one-half of the internal diameter of the pump-barrel. It will thus be seen that whereas in the old form of valves only 35 a very narrow annular space was provided for the escape of the borings, sand, or gravel, and also of stones, pieces of rock, sand, gravel, and other obstructions, in this invention a space equal to or exceeding the radius of the 40 tube is afforded.

The length of the valve-opening may of course be varied within wide limits, and in this way sufficient weight may be obtained before 45 it reaches the bottom of the well. It is found, also, that the valve works better, is more positive in its action, and cheaper to construct than any of the old forms.

I do not intend to be restricted to the exact 50 form or proportions of the parts shown in the drawings, as it is obvious they may be changed without departing from the spirit and scope of my invention.

Although I have shown and described a 55 pump-barrel as cylindrical and have claimed the valve and its opening as segmental, I wish it distinctly understood that the pump-barrel may be of any other cross-section, and that when a pump-barrel of any other than a 60 cylindrical cross-section is used the valve and the valve-opening will be correspondingly changed.

I hold my invention to cover any form of pump-barrel and any form of valve and valve-opening used in connection therewith so long 65 as the valve and its opening are longitudinal sections or segments of the barrel.

What I claim, and desire to secure by Letters Patent, is—

1. In a sand-pump, the combination of a 70 segmental valve-opening in the side at the lower end of the barrel and an interiorly-arranged sliding segmental valve adapted to fit into the barrel and open and close said opening. 75

2. In a sand-pump, the combination of the barrel, a segmental valve-opening in the side at the lower end of the barrel, and a segmental 80 gravitating valve arranged to slide within the barrel to open and close the opening, said valve having a stem projecting beyond the end of the tube.

3. In a sand-pump, the combination of the barrel, a segmental valve-opening in the side at the lower end of the barrel, a segmental 85 gravitating valve arranged to slide within the barrel, a stem for the valve projecting beyond the end of the barrel, and a stop to prevent the passage of the valve too far up into the barrel. 90

4. In a sand-pump, the combination of the barrel, a segmental valve-opening in the side at the lower end of the barrel, a segmental 95 gravitating valve arranged to slide within the barrel, a stem for the valve projecting beyond the end of the barrel, and a guide for the valve within the barrel.

5. In a sand-pump, the combination of the barrel *A*, the cap *D* on its lower end, the segmental valve-opening *d* in the cap, the segmental 100 gravitating valve *E*, arranged to slide within the barrel, the stem *s*, playing in a notch in the end of the cap, the cross-head *d'*, working in the barrel, and the foot *f* on the end of the stem, substantially as described. 105

6. The combination, to form a sand-pump, of the barrel *A*, closed at the top by the plug *B*, having the yoke *F*, the openings *C*, the cap *D* on the lower end of the barrel, the pump *P P'*, the segmental valve-opening *d* in the 110 cap, the segmental gravitating valve *E*, arranged to slide within the barrel, the stem *s*, playing in a notch in the end of the cap, the cross-head *d'*, working in the barrel, and the foot *f* on the end of the stem, substantially 115 as described.

In testimony whereof I affix my signature in presence of two witnesses.

JOHN BRADEN.
